UNITED STATES PATENT OFFICE.

JOHN I. SABIN, OF SAN FRANCISCO, CALIFORNIA, ASSIGNOR TO THE AMERICAN BELL TELEPHONE COMPANY, OF BOSTON, MASS.

TELEPHONE-EXCHANGE SYSTEM AND APPARATUS THEREFOR.

SPECIFICATION forming part of Letters Patent No. 249,262, dated November 8, 1881.

Application filed April 26, 1881. (No model.)

To all whom it may concern:

Be it known that I, JOHN I. SABIN, of San Francisco, California, have invented certain new and useful Improvements in Switch-Boards for Telephone-Exchanges, of which the following specification is a full description.

This invention relates more especially to an organization of electric circuits and apparatus known as a telephonic-exchange system, where-
10 by direct inter-communication can be estab-
lished over telegraph or telephone lines extend-
ing in different directions from a central sta-
tion or exchange between a number of separate
substations situated at various points within
15 the geographical district which the central sta-
tion is designed to serve. The organization
and arrangement of the lines, commutators, and
apparatus in the exchange or central station is
such that any two substations within the dis-
20 trict may at a moment's notice be placed in di-
rect telegraphic or telephonic communication
by the act of an operator or attendant who is
kept constantly on duty at the central station,
and who, upon being notified to do so by a sub-
25 scribe or other person at a substation, unites
the terminals of the two lines which are de-
sired to be connected together by means of
suitable switching or connecting devices pro-
vided for this purpose.

30 The present invention consists, mainly, in certain improvements upon a system and ap-
paratus of this character shown and described
in my former Letters Patent of March 29, 1881,
No. 239,557, whereby the connection and dis-
35 connection of lines may be effected with great-
er convenience and facility than has heretofore
been possible, especially in exchanges where a
very large number of wires are assembled to-
gether.

40 The particular combinations of mechanism
which constitute the subject-matter herein
claimed as new are more particularly design-
ated in the claims at the end of this specifica-
tion.

45 In the accompanying drawings, Figure 1 is
a diagram illustrating the organization of a cen-
tral or exchange station, showing the relations
of the various parts of the apparatus to each
other and illustrating the method of opera-
50 tion. Fig. 2 is a detailed sectional view of the
switch-plug or connector.

Referring to Fig. 1, A represents a group of
line-wires entering the central or exchange
station. Each wire extends to the residence
or place of business of an individual subscriber
55 within the district, or, as it will be hereinafter
termed, to a "substation." The drawings show
but four of these lines, which is a sufficient
number for the purpose of illustration, but the
number will ordinarily be much greater than
60 this, and in important stations there may be
several hundreds of such lines converging to
the exchange as a common center. At the dis-
tant end of each substation-line is placed a sig-
nal apparatus, which may consist of a battery
65 and key or of a magneto-electric generator, to-
gether with a transmitting and receiving tele-
phone. All these several devices and their ar-
rangement at the substation, in connection
with the line, are well known, and therefore do
70 not require detailed description.

B and B' are two duplicate switch-boards,
each of which is composed of an assemblage
of separate commutators equal in number to
the number of lines to be provided for, and
75 compactly arranged upon a non-conducting
base-board. Each commutator consists of three
detached sections, a b c, which are preferably
constructed in the form shown in the drawings,
so that they each occupy a space of about three-
quarters of an inch square upon the switch-
board. The number of duplicate switch-boards
B and B' will depend upon the number of lines
entering the office. When the number is not
80 very great a single switch-board, as B, having
a number of separate commutators upon it
equal in number to the lines to be provided
for, will be sufficient; but when the number of
lines entering the exchange becomes greater
85 than can be promptly attended to by a single
operator, then a duplicate switch-board, as B',
is provided, at which a second attendant may
be stationed, and in this manner the labor may
be subdivided to any required extent as the
90 number of lines increases. Each line-wire is
connected with its corresponding commutator
in each switch-board, and each commutator
should be marked with a number correspond-
ing to the number designating the line to which
it appertains. The upper section, a, of each
95 commutator is connected with its correspond-
ing line-wire. The lower right-hand section,
100

e, of each commutator of the switch-board B is united to a common wire, *d*, which extends to a local battery, E, the other terminal of which is connected directly to the ground at 5 G. In like manner the lower right-hand section of each commutator of the switch-board B' is connected by a common wire, *d'*, to another local battery, E', and thence to the ground at G. A single local battery might serve for two 10 or more switches; but it is usually preferable to employ a separate battery for each switch.

The lower left-hand section, *b*, of each commutator is connected by a special electro-magnet, H, by means of a wire, *b'*, and thence directly to the ground at G by means of wire *g*. 15 Each separate line is provided with an electro-magnet, F, the office of which is to operate a switch for the purpose of directing the circuit of said line through a receiving-telephone, at 20 which an attendant is stationed, who is able to hear what is said by the person at the substation. The arrangement of the connections of each separate main circuit in the central office is the same, and will be most readily understood 25 by tracing the course of some one line—for example, line No. 143 of the group entering the station at A. This line connects by means of a branch wire with the upper section of the commutator 143 in switch B, and 30 in like manner with the upper section of the commutator 143 of switch B', and from thence it proceeds to the armature-lever *h* of its corresponding automatic switching device, by means of which the main-line circuit is connected with one or the other of two branch lines, 35 as hereinafter explained. When all the parts are in their normal position of rest the armature-lever *h* is held in place against the tension of the spring *h*² by means of a latch or detent, 40 *f'*, formed upon the extremity of the armature *f* of a second electro-magnet, F. When all the parts are in the position just described the circuit of the main line 143 passes through the armature-lever *h* to the armature-lever *f*, 45 with which it is in contact, and thence by wire *g* through the electro-magnet F and to the earth at G. Hence, when an electric current from the substation traverses line 143, the electro-magnet F, and earth-circuit *g* to ground 50 G, the said magnet F lifts its armature *f* and releases the armature *h*. The latter is instantly drawn back by the spring *h*², and the connection between the main line and the branch or earth circuit *g* is interrupted and a new circuit formed through the branch *m* by the armature *h* coming in contact with the stop *h'*. 55 *o* is a normally-open earth-circuit, in which is included a receiving-telephone, T, and this circuit is connected by means of branches *m* 60 *m m m* with the stops *h'* of every annunciator in the series. *r* is another open earth-circuit, terminating in a metallic peg, *p*, with a suitable handle, and including a testing apparatus, R, which may be of any description capable 65 of indicating the presence of an electric current in the wire. I prefer to employ for this purpose an ordinary electro-magnetic bell, as

shown in the figure, but a galvanometer or any known apparatus serving the same purpose may be employed.

The connection between two lines entering the central station is effected by means of an ordinary flexible connection, usually termed a "switch-cord," which is armed at each end with a switch-plug constructed as hereinafter described. A portion of the cord and one of the switch-plugs is shown in detail in Fig. 2. The handle *W* of the plug is of a cylindrical form, and made of some insulating material, such as hard rubber. It is provided with a 80 prolongation, *w*, of smaller diameter. Upon the under side of this prolongation is fastened a metallic plate, *z*, by means of screws or otherwise, and upon the upper side is fixed another metallic plate, *y*, which is made in the form of a 85 spring, and works in a groove in the handle of the plug at *y'*, and is attached to the conducting-cord *x* at the point of the plug by means of a screw, *v*, or otherwise. Thus it will be understood that the conducting-cord *x* is in 90 electrical connection with the upper spring, *y*, of the plug, while the lower plate, *z*, is entirely insulated.

The operation of the improved apparatus is as follows: Let it be supposed that a person at 95 the substation of line 143 wishes to be placed in direct communication with the substation of line 141. He first transmits a call-signal to the central office, consisting of an electric current which instantly traverses the electro-magnet F of the automatic switch, as previously explained, transfers the connection of the main line to the branch line *m* and earth-circuit *o*, containing the telephone T, at which the receiving-operator is stationed. Immediately after transmitting the call-signal the substation-operator speaks through his telephone, and gives the number or name of his substation-line and that of the substation-line—in this case 141—with which he desires connection. This will be heard by the receiving-operator, who will then take a switch-cord and insert one of its plugs in the commutator of line 143 and the other one in commutator of line 141. This operation will form a direct 105 connection between the upper sections of the two commutators by means of the switch-cord, while at the same time the two lower plates, *b* 110 *c*, of each commutator 141 and 143 will be connected with each other by means of the plate *z*, upon the under side of the plug, which will 115 close a local circuit from the battery E through the wire *d* to the section *c* of commutator of 143 in switch B, thence to the section *b* of the same, thence by wire *b'* to electro-magnet H, 120 thence by wire *g* to the other pole of the battery E. The closing of this local circuit will bring the electro-magnet H into action, which 125 will instantly attract its armature *h*. The two lines being thus connected together through 130 the switch-cord, the sub-stations 143 and 141 may correspond directly with each other. The armature-lever *h*, being now held close to the poles of the local electro-magnet H, is not in con-

tact with the detent f' , consequently the connecting of both main lines with the earth is thereby interrupted so long as the local circuit is closed at the switch.

5 In case two or more duplicate switch-boards are employed in an exchange, it is necessary, after receiving a call for a connection with a particular line, to ascertain whether or not that line is already in use. For this purpose I make 10 use of the open earth-circuit r and testing-instrument R , it being only necessary for the operator, before making the connection, to touch the metallic peg p , which is in connection with the wire r , to the lower left-hand section of the 15 commutator of that particular line. If the line is in use a current from the local battery E will pass through the testing-instrument and actuate it, because the circuit is already closed by the insertion of a switch-plug in the corresponding connector of one of the other switches, and the testing-instrument therefore will respond; but if the line is not in use no plug will be inserted, and consequently the left-hand section of the commutator will have no battery- 20 connection and the testing-instrument will not respond. In this way it may at once be ascertained by the operator whether or not that particular line is in use.

Having now fully described my said invention, and the manner of carrying the same into effect, what I claim is—

1. In a system of electrical communication, the combination of two or more switch-boards connected each with the several line-circuits 35 entering the central station by branch wires, an electric switch or circuit-changer actuated by an electro-magnet in a branch circuit normally connected to each main circuit and adapted to transfer the main circuit from 40 said branch to a normally-open branch circuit, which includes a telephone or telephones, means for automatically restoring the circuit-changers and main-line circuits to their normal positions, and a normally-open testing-circuit, 45 including an electro-magnetic testing-instrument, with means for connecting the same to any particular line for the purpose of ascertaining whether such line is already in use, substantially as described.
- 50 2. In a telephone-exchange system, the combination, with a main-line circuit and an automatic electric switch or circuit-changer in said circuit for altering the connections thereof, of means whereby the electric switch or circuit-changer and the main-line circuit connections are automatically restored to their normal positions, said means consisting of an independent circuit normally open, an electro-magnet included in said circuit, a circuit-closer, and a 55 double connector or switch plug, which, when put into position for connecting one line with another, is adapted to operate said circuit-closer, substantially as described.
- 60 3. The combination, substantially as herein-

before set forth, with a line-circuit and automatic electric switch in said circuit for altering the connections thereof, of a commutator or switch having three contacts, one connected to the line, one to the battery and earth, and one to an electro-magnet acting to restore the 65 automatic switch of said line to its normal position, a contact-peg forming the terminal of a normally-open earth-circuit, and an electromagnetic testing device included in said open earth-circuit, substantially as described. 70

4. The combination, substantially as hereinbefore set forth, of a commutator or switch having three contacts, one connected to the line, one to the battery and earth, and one to an electro-magnet acting to restore the automatic switch of said line to its normal position, 80 with a contact-peg forming the terminal of a normally-open earth-circuit, and an electromagnetic testing device included in said open earth-circuit, substantially as described. 85

5. The combination, with an automatic electric switch or circuit-changer acting to alter the connections of the line on which it is placed, of an electro-magnet acting by the attraction of its armature to interrupt said line and to 90 bring the several parts into position for re-establishing the normal condition of the circuit when the armature is released or drawn back, substantially as described.

6. The combination, with one or more switch-boards and lines centering therein, of a series 95 of automatic switches or circuit-changers for altering the electrical connection of said lines, and a series of electro-magnets for restoring the said switches to their normal position, substantially as and for the purpose set forth. 100

7. The combination, with one or more switch-boards, a series of line-circuits connected with 105 said switch-boards, and a series of automatic electric switches in said line-circuits, of electrically-operated devices for restoring said switches to their normal position, and means, as explained, for automatically bringing said devices into action in establishing connection on the switch-board between said line-circuits, 110 substantially as described.

8. The combination, substantially as hereinbefore set forth, of two or more main signaling-circuits converging to a common receiving-station, each of said circuits being provided with, 115 first, a branch circuit normally in electric connection with the main circuit; second, a switch or circuit-changer actuated by an electro-magnet included in said branch circuit, which, when thus actuated, transfers the connection 120 of said main circuit to a normally-open earth-circuit, which is common to all the main circuits when thus transferred; and, third, an electro-magnet in an independent circuit for restoring said circuit-changer and main-line 125 circuit to their normal positions.

JOHN I. SABIN.

Wm. Sabin 7/2
